US0D1033407S

(12) **United States Design Patent** (10) **Patent No.:** **US D1,033,407 S**
(45) **Date of Patent:** **** Jul. 2, 2024**

(54) **MICROPHONE**

(71) Applicant: **Audio-Technica Corporation**, Tokyo (JP)

(72) Inventor: **Ren Yoshioka**, Kanagawa (JP)

(73) Assignee: **AUDIO-TECHNICA CORPORATION**, Tokyo (JP)

(**) Term: **15 Years**

(21) Appl. No.: **29/793,099**

(22) Filed: **May 12, 2021**

(30) **Foreign Application Priority Data**

Nov. 18, 2020 (JP) ..... 2020-024822 D

(51) **LOC (14) Cl.** **14-01**

(52) **U.S. Cl.**

USPC **D14/225**; D14/228

(58) **Field of Classification Search**

USPC D14/155-159, 160-173, 187-188, D14/189-198, 203.1-203.8, 204-216, D14/217-222, 223, 224-229, 239, D14/251-253, 257-258, 335-337, D14/371-382, 432, 439-441, 447-452, D14/457, 496, 498-506; D6/672-673, D6/675.1, 682; D26/60-63

CPC H04R 1/02; H04R 1/021; H04R 1/025; H04R 1/026; H04R 1/028; H04R 1/06; H04R 1/105; H04R 1/323; H04R 1/403; H04R 1/2803; H04R 1/2834

(57) **CLAIM**

The ornamental design for a microphone, as shown and described.

DESCRIPTION

FIG. 1 is a front perspective view of a microphone showing the new design;

FIG. 2 is a rear perspective view of the microphone;

FIG. 3 is a front elevational view of the microphone;

FIG. 4 is a rear elevational view of the microphone;

FIG. 5 is a top plan view of the microphone;

FIG. 6 is a bottom plan view of the microphone;

FIG. 7 is a right side elevational view of the microphone; and,

FIG. 8 is a left side elevational view of the microphone.

Portions of the microphone shown in broken lines form no part of the claimed design.

1 Claim, 8 Drawing Sheets
